UNITED STATES PATENT OFFICE.

HARRY CLIFTON CROSBY, OF NEW YORK, N. Y.

FOUNTAIN-PEN.

1,190,867.

Specification of Letters Patent. Patented July 11, 1916.

Application filed December 22, 1914. Serial No. 878,613.

To all whom it may concern:

Be it known that I, HARRY C. CROSBY, a citizen of the United States of America, and residing at New York, in the county of 5 New York and State of New York, have invented new and useful Improvements in Fountain-Pens, of which the following is a specification.

One object of my invention is the provision of a simple and efficient fountain pen 10 for writing in different colors or kinds of ink.

A special feature of the invention is that I employ only a single pen point instead of 15 a point for each ink as in pens of this general character heretofore proposed.

Briefly considered the invention resides in combining with a pen barrel provided with suitable reservoirs for the different inks, a 20 writing point which can be so arranged as to take ink from any reservoir.

In the embodiment herein disclosed a feed spoon is connected with each reservoir and the feed spoons not in use are retracted by a 25 simple turning movement of one part of the barrel in respect to another part. The pen point also is capable of retraction and the transposition of the point from register with one feed spoon to another is effected in the 30 relative turning movement of the two parts of the barrel.

Another special feature of the invention is the provision of means for automatically wiping off the pen point so that it will be 35 cleaned of one ink before being used with another ink.

Various other features will appear as the specification proceeds.

The accompanying drawing illustrates in 40 concrete form a practical embodiment of my invention but it will be understood that various changes and modifications may be made without departure from the true spirit and scope of the invention.

45 Figure 1, is a top view of a pen constructed in accordance with and embodying the invention. Fig. 2, is a longitudinal sectional view of the same. Fig. 3, is a cross sectional view taken substantially on the 50 plane of the line 3—3 of Fig. 2. Fig. 4, is a broken plan view of the guiding and supporting means for the feed spoons. Fig. 5, is a view of the lower section of the barrel.

55 The pen illustrated is for writing in two kinds of ink, say black and red, so two ink reservoirs, designated 7 and 8 are therefore

provided in the barrel or body of the pen. These reservoirs are shown as of the "self-filling" type, in the form of rubber sacks which can be collapsed by means of the 60 presser plates 9 and 10 having exposed finger pieces 11 and 12.

A single pen point 15 is provided and this is so mounted that it can be transposed to draw ink from either reservoir. In the specific disclosure made herein this transportation is accomplished by retracting the pen point from operative relation to a feed spoon for one kind of ink, relatively rotating the pen and reservoir to carry the retracted pen into register with a feed spoon 70 for the other ink and then projecting the pen into position over the second feed spoon.

The pen is accordingly shown as carried by a holder 17 slidably mounted within the 75 lower end portion of the barrel and provided with a stem 18 projecting up through a slot 19 in the barrel, said stem having a finger cup 20 on its upper end by which the holder slide is operated. The relative 80 rotative movement is obtained by making the barrel in two relatively rotatable parts, an upper section 22 and a lower section 23, the upper section carrying the ink reservoirs and the lower section carrying the pen point. 85

The two feed spoons, are designated 25 and 26, the first being connected with the black ink reservoir 7 by a tube 27 and the other being similarly connected with the red ink reservoir 8 by a tube 28. These feed 90 spoons are shown as arranged in the relative rotation of the barrel sections to be the one retracted into the barrel and the other projected into position for use, such reverse movements being obtained by providing the 95 spoons with lugs 29 and 30 engaging reversely inclined shoulders provided by the reversely inclined cam grooves 31 and 32 on the inner wall of the lower barrel section. The feed spoons are disposed on opposite 100 sides of a combined supporting and guiding bar 33, and they are shown as confined to said bar by an encircling guide ring 34 which is secured to the lower end of the bar. The spoons are so shaped as to provide a 105 space 35 between the back of the spoon and the inclosing guide ring through which the pen point can be projected.

The ink supply tubes 27 and 28 are preferably rigid so as to assist in guiding the 110 feed spoons. Thus in the illustration each feed spoon is formed with a longitudinal

bore 37 to receive the end of its supply tube, the fit being such that the spoon will slide easily over the tube. The spoon is provided with a feed passage 38 leading off from the bore 37, preferably at a point inward from the end thereof so as to be cut off by the supply tube when the spoon is in retracted position (see Fig. 2).

The guiding and supporting bar 33 is shown as extending full length of the upper barrel section so as to constitute a partition separating the two ink reservoirs and it is shown as supported therein by reason of its engagement with the inner walls of the barrel section and by being passed through a supporting plug 40 closing the lower end of the section. The supply tubes are also supported in this plug, the inner ends of the tubes projecting far enough up into the upper barrel section for the necks of the ink sacks to be slipped thereover.

In the construction disclosed the two sections of the barrel are revolvably held together by means of an abutment ring 50 which bears against the end of the lower barrel section and has a screw threaded engagement over the guide ring 34.

To automatically clean the pen point of ink I have provided wiping material 60, disposed in position to be engaged by the pen point in the transposing movement thereof, this wiping material being in the illustration in the form of an annular gasket of leather or like material which is clamped by the abutment ring 50 against the end of the guide ring in position to engage the outer surface of the pen point. This gasket is, as shown, preferably so positioned as to register with the feed outlets 38 in the feed spoons when the feed spoons are in retracted position. The gasket therefore constitutes a substantial closure to the feed outlet of the spoon which is in the retracted position of nonuse.

45 A further wiping effect is obtained in the present disclosure by providing a second body of wiping material, shown in the form of a ring 65 of leather or the like, seated in an annular grooveway 66 on the interior 50 of the abutment ring 50 at a point in advance of the first body of wiping material.

From the foregoing it will be evident that to change from one ink to another, it is merely necessary to retract the pen point 55 to a position where it will clear the feed spoon with which it has been coöperating, then to relatively rotate the two barrel sections a half revolution and then to project the pen point over the new feed spoon with 60 which it has been brought into register by the relative rotary movement of the barrel sections. The cup-shaped finger piece 20 by which the pen point is retracted and projected forms a very convenient rest for the

finger in writing and so is an advantage 65 aside from its function of shifting the pen.

During the retractive movement of the pen point the wiping devices will automatically remove the surplus ink from the pen point. In the part rotary movement of the 70 relatively movable parts a rotary wiping action on the pen point will be produced and as the pen point is projected into position for use with the fresh feed spoon a second longitudinal wiping effect will occur. This wiping of the pen point is sufficient ordinarily to remove all traces of the last ink used.

When a feed spoon is retracted, the supply of ink thereto is automatically cut off 80 by the closing of its supply tube and the possible escape of any ink remaining in the feed passage is prevented by the substantial closure of the said feed passage by the first wiping device 60. This wiping device 85 also will act to prevent leakage of ink if for any reason the ink supply should not be properly cut off.

The parts, it will be noted are all of very simple and inexpensive construction and 90 those parts which may need renewing, such as the wiping devices, are so located and supported that they can be readily replaced when needed.

What I claim is:—

1. In a fountain pen, a barrel provided with reservoirs for different colored inks, a feed spoon connected with each reservoir, a common pen point for the several inks, and means for operatively associating the said pen point with any one of the feed spoons.

2. In a fountain pen, a barrel made up of relatively rotatable sections, reservoirs for different colored inks in one of said sections, a support carried by said section projecting into the other section, retractable feed spoons slidingly mounted on opposite sides of said support and connected with the ink reservoirs, outstanding lugs on the feed spoons and reversely arranged internal cam shoulders on the other relatively rotatable barrel section engaging the said lugs to project one feed spoon while retracting the other feed spoon upon relative rotation of 110 the barrel sections.

3. In a fountain pen, a barrel provided with reservoirs for different colored inks, a feed spoon connected with each reservoir, a common pen point for the several inks, means for projecting the feed spoon of the ink to be used and simultaneously retracting the feed spoons not in use into the barrel, and means for operatively associating the pen point with the projected feed spoon.

4. In a fountain pen, a barrel made up of relatively rotatable sections and provided with reservoirs for different colored inks,

feed spoons carried by one of the barrel sections and connected with the ink reservoirs and a pen point mounted on the other barrel section and carried by relative rotation thereof into register with any one of the feed spoons.

5. In a fountain pen, a barrel made up of relatively rotatable sections and provided with reservoirs for different colored inks, 10 feed spoons carried by one of the barrel sections and connected with the ink reservoirs, a retractable pen point mounted on the other relatively rotatable barrel section and means for retracting and projecting the 15 said pen point, whereby said pen point may be retracted and the barrel sections be relatively rotated to bring the pen point into register with another one of the feed spoons and the pen point be then projected over the 20 said feed spoon.

6. In a fountain pen, a barrel, a retractable pen point carried thereby, means for retracting said pen point into the barrel and relatively stationary wiping material in the 25 end of the barrel in position to be slidingly engaged by the pen point as the same is retracted to thereby remove the surplus ink from said pen point.

7. In a fountain pen, a barrel made up of 30 relatively rotatable sections and provided with reservoirs for different colored inks, retractable feed spoons carried by one of the barrel sections and connected with the ink reservoirs, lugs on the feed spoons, reversely arranged cam shoulders on the other 35 barrel section engaging the said lugs whereby upon relative rotation of the barrel sections to project one feed spoon while retracting another feed spoon, and a pen point 40 mounted on the latter barrel section and carried by the relative rotation thereof into register with the projected feed spoon.

8. In a fountain pen, a barrel made up of relatively rotatable sections and provided 45 with reservoirs for different colored inks, retractable feed spoons carried by one of the barrel sections, and connected with the ink reservoirs, lugs on the feed spoons, reversely arranged cam shoulders on the other 50 barrel section engaging the said lugs whereby upon relative rotation of the barrel sections to project one feed spoon while retracting another feed spoon, a retractable pen point mounted on the latter barrel section and carried by the relative rotation 55

thereof into register with the projected feed spoon and means for projecting the pen point over the said projected feed spoon.

9. In a fountain pen, a barrel composed of upper and lower relatively rotatable sections, ink reservoirs in the upper barrel section, a guide extending from said upper section down into the lower barrel section, retractable feed spoons slidably supported by 60 said guide and connected with the ink reservoirs, cam connections between said feed spoons and the lower barrel section whereby upon relative rotation of the barrel sections one feed spoon will be retracted and another feed spoon will be projected and a pen point 65 on the lower barrel section carried by the relative rotation thereof into register with the projected feed spoon.

10. In a fountain pen, a barrel composed of upper and lower relatively rotatable sections, ink reservoirs in the upper barrel section, a guide extending from said upper section down into the lower barrel section, retractable feed spoons slidably supported 70 by said guide and connected with the ink reservoirs, cam connections between said feed spoons and the lower barrel section whereby upon relative rotation of the barrel sections one feed spoon will be retracted and another feed spoon will be projected 75 on the lower barrel section carried by the relative rotation of the barrel sections into register with the projected feed spoon.

11. In a fountain pen, a barrel provided 80 with reservoirs for different colored inks, a feed spoon connected with each reservoir, a pen point movably supported in relation to the feed spoons to thereby permit of said pen point being associated with different 85 ones of the feed spoons and a wiping material supported in the path of movement of the pen point for freeing said pen point of the ink last used thereby.

12. In a fountain pen, a barrel provided 90 with reservoirs for different inks, a single pen point, means for shifting said pen point into ink feeding relation to different ones of the reservoirs and means for automatically wiping off said pen point in the said 95 shifting movements thereof.
